UNITED STATES PATENT OFFICE.

EZRA SPENCER DODGE, OF PROVIDENCE, RHODE ISLAND.

DESIGN FOR A JEWELER'S FINDING-STRIP.

SPECIFICATION forming part of Design No. 19,834, dated May 13, 1890.

Application filed January 31, 1890. Serial No. 338,811. Term of patent 7 years.

To all whom it may concern:

Be it known that I, EZRA SPENCER DODGE, a citizen of the United States, residing at Providence, in the State of Rhode Island, have invented and produced a new and original continuous Design for the Surface Ornamentation of Jewelers' Finding-Strips, of which the following is a specification, reference being had to the accompanying drawings, forming a part thereof.

Figure 1 represents the front view of a jeweler's finding-strip having a surface ornamented with my design. Fig. 2 represents a central longitudinal section of the same.

My new design for the surface ornamentation of finding-strips consists in a series of adjoining hexagons formed by depressions or recesses made in triangular pyramid form, the diagonals of the hexagons and the lines of their separation being formed at the top of the ridges between the said depressions or recesses and in the plane of the face of the finding-strip.

In the accompanying drawings, A represents a continuous finding-strip, upon one side of which are formed the recesses *b b b*, which have a triangular base lying in the plane of the surface of the strip, and a centrally-arranged apex *c*, the triangular recesses *b* being so arranged as to form the continuous series of adjoining hexagons *d d d* with the diagonals *e e e*, and the lines of separation *f* lying in the plane of the surface of the strip, as shown in Fig. 2.

What I claim is—

In a design for the surface ornamentation of jewelers' finding-strips, the pyramidal recesses having triangular bases arranged to form a continuous series of hexagons, which have the diagonals *e e e*, and the lines of separation *f* in the plane of the face of the strip, as set forth.

EZRA SPENCER DODGE.
